SLED CONSTRUCTION

Hakon E. Gilbert, Brooklyn, N. Y.

Application September 11, 1936, Serial No. 100,243

1 Claim. (Cl. 280—23)

This invention relates to a sled, toboggan or similar article.

The main object of the invention is to provide a sled of simple and firm construction which may be collapsed at will in order to facilitate transportation and storage.

Another object is to provide a sled which affords a comfortable seat for the passenger and which may be propelled from behind by pushing or kicking with one foot.

Still another object is to provide a sled which may be easily steered and the speed of which may be controlled by simple manipulation of the foot.

Other objects and advantages will become apparent as the specification proceeds and which is taken in connection with the accompanying drawing illustrating by way of example a preferred embodiment of the inventive concept.

In the drawing:

Figure 1 is a side view of a sled or toboggan according to the invention showing the collapsible feature in dotted lines.

Figure 2 is a top plan view.

Figure 3 is a section along the line 3—3 of Figure 1.

Figure 4 is a section along the line 4—4 of Figure 2.

Figure 5 is a detail view of a portion of the front part of the sled.

Having reference to the drawing, 10 indicates the runners. These runners are elongated and extend a substantial distance in back of the back supports 11 for the purpose which will hereinafter be described.

The runners 10 are bent upward at the front to form a bow for the sled. A crossbar 12 is pivoted to the two runners. The arched supports 13 are pivoted to the back support 11 at 14 and are connected by means of a crossbar 15 and 16 at the rear and front respectively.

A plurality of strips 17 are attached to the arched supports 13 to provide a seat.

The front crossbar 16 is provided with pins 18 which normally rest in slots 19 on the crossbar 12 and are held in place by latches 20 comprising a bolt 21 reciprocable within the housing 22. Thus the frame composed of the parts 13—15—16 may be lifted from the slots 19 by

simply withdrawing the bolt 21 by means of the handle 23.

The back supports 11 are pivoted to the runners 10 at 24 and thus the entire chair portion composed of the parts 13—15—16 and 11 may be folded down substantially flush with the runners.

The back supports 11 are preferably connected at the upper ends by a crossbar 25 which also serves as a handle in pushing the sled.

The rear portion of the runners 10 are provided with foot rests 26 and 27 upon which the tobogganist may stand when coasting the sled. The position of these foot rests may be adjusted according to the needs and desires of the individual tobogganist by means of the clamps 28 15 normally pressing against the runner.

A brake comprising a flexible strip 29 provided with a hook or a claw 30 is mounted on a crossbar 31. This crossbar is pivoted to the runners 10 at 32 and 33 in order not to interfere with the steering of the sled. Braking may be effected simply by pressing down the strip 29 with the foot.

The sled may be steered by exerting pressure on the handle 25 in the direction in which motion 25 is desired and which operation will cause the runners being relatively displaced. The steering may be facilitated by shoving either runner outwardly. In other words, they may be used as rudders during the coasting of the sled. In order 30 to serve this purpose properly, the runners should extend a considerable distance beyond the chair portion of the sled.

What is claimed is:

A collapsible sled having a pair of parallel 35 runners bent at their forward end to form a bow, a pair of normally upright supports for pushing the sled pivoted at their lower ends to said runners, a cross bar connecting the forward ends of said runners, a seat frame pivotally secured at 40 the rear end to said supports to form a permanent connection, a cross bar connecting the forward end of said seat frame, studs projecting from said last mentioned cross bar and said first mentioned cross bar being notched to receive said studs and locking means carried by said first mentioned cross bar to lock said seat frame in position when the sled is assembled for use.
